UNITED STATES PATENT OFFICE.

JOSEPH S. KAUFMAN AND ISAAC KAUFMAN, OF BALTIMORE, MARYLAND.

BOTTLE-CAP.

1,124,141.

Specification of Letters Patent.

Patented Jan. 5, 1915.

Application filed August 12, 1913. Serial No. 784,424.

To all whom it may concern:

Be it known that we, JOSEPH S. KAUFMAN and ISAAC KAUFMAN, citizens of the United States, residing at Baltimore, in the State of Maryland, have invented new and useful Improvements in Bottle-Caps, of which the following is a specification.

This invention relates to bottle caps; and it has for its primary object the provision of a device of this character which will serve to completely close the upper end of the bottle and to prevent foreign matter or liquid from accumulating within the neck and from entering the contents of the bottle.

Another object of this invention is the provision of a sanitary device of this character, which will eliminate the possibility of the liquid becoming contaminated and which will be so constructed as to facilitate the operation of applying the cap to or removing the same from the neck of the bottle as the occasion may demand.

With these and other objects in view, the invention consists of certain novel features of construction, combination and arrangement of parts, as will be hereinafter described and claimed.

In the accompanying drawings:—Figure 1 is a perspective view, illustrating the initial operation of applying the cap to the bottle neck; Fig. 2 is a similar view showing the cap in its applied position; Fig. 3 is an edge view thereof; Fig. 4 is a horizontal section on the line 4—4 of Fig. 3; Fig. 5 is a plan view of a portion of the blank from which the cap is formed; and Fig. 6 is a vertical section through a portion of the bottle, showing the application of the cap thereto.

The cap 1 herein illustrated is designed particularly for use upon milk bottles or the like for sealing the neck in such manner as to minimize the possibility of the elements entering the bottle and mixing with the original contents thereof. The cap may be constructed of any suitable well known elastic material having a uniform thickness throughout and stamped or otherwise suitably formed so as to provide a main crown 2 which overlies the neck and which is extended into an elastic concavo-convex rim or flange 3. The material in the flange forming portion 3 thereof is provided at spaced intervals with extensions 4 having angular

edges 5 extending in opposite directions and gradually merging into the lower edges of adjacent portions of the flange or rim 3. The extensions 4 are designed to give to the rim or flange 3 an extra fullness of material so that under the inherent elasticity of the metal, the flange is expandible and may be readily sprung over the bead 6 of the bottle 7 herein shown whereby to effectually embrace the bead and to form a seal around the neck of the bottle to minimize the possibility of outside elements entering the bottle and mixing with the contents thereof. Each portion 4 is provided with a weakened line 8 which terminates directly at the juncture of the flange or rim 3 with the crown 2. Each extension is thus formed so that it may be folded on itself as shown particularly in Fig. 4, providing substantially accordion-like folds 9, which are adapted for relative separation during the operation of forcing the flange 3 over the bead 6 of the bottle neck.

The construction of the device is such that while the operation of applying the device to the bottle is greatly facilitated the corners 10 of the extension 4 are disposed in positions normally whereby to permit of their being engaged by the fingers of the hand and pressure of the hand applied thereto in an upper direction during the operation of removing the cap from the bottle.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention as claimed.

Having thus described our invention, what we claim is:—

A bottle cap constructed of a single blank of sheet material provided with a crown having a depending normally concavo-convex flange provided with a pair of spaced extensions, each of said extensions being weakened on an uneven number of lines which are disposed in converging relation in the direction of the edge of the crown and which extend throughout the width of the flange, each of said extensions being

folded on itself on the weakened lines and arranged so that its folds are relatively separable to respectively permit the flange to be extended and contracted and to also permit that portion of the flange between said extensions to be grasped by the hand during the operation of removing the cap from the bottle or applying the same thereto.

In testimony whereof we affix our signatures in presence of two witnesses.

JOSEPH S. KAUFMAN.
ISAAC KAUFMAN.
